(57) **CLAIM**

The ornamental design for a tire tread, as shown and described.

DESCRIPTION

FIG. 1 is a perspective view of a tire tread in accordance with the invention;

FIG. 2 is a front elevation view thereof;

FIG. 3 is a partial front elevation view thereof, shown at an enlarged scale;

FIG. 4 is a side elevation view of inside of the tire tread; and,

FIG. 5 is a side elevation view of outside of the tire tread. The broken lines depict environmental subject matter only and form no part of the claimed design.
